UNITED STATES PATENT OFFICE.

WALTER P. MURPHY, OF CHICAGO, ILLINOIS.

ROOF-CLIP FOR CAR-ROOFS.

1,006,496.

Specification of Letters Patent. Patented Oct. 24, 1911.

Application filed December 24, 1910. Serial No. 599,206.

To all whom it may concern:

Be it known that I, WALTER P. MURPHY, a citizen of the United States, and a resident of the city of Chicago and State of Illinois, 5 have invented a new and useful Improvement in Roof-Clips for Car-Roofs.

In sheet metal roofs of the outside type, where the sheet metal covering is fully exposed to the weather and to the wear and 10 tear of service, it has been found that the sheets give way first near the standing seams, particularly at the eaves where the sheets are held down by clips. This is due in part to the "weaving" or "racking" of the car 15 body setting up stresses tending to tear the sheets, which stresses are concentrated at the points where the sheets are held down on the roof substructure, and in part to the greater liability of the sheets to rust out under the 20 clips on account of the constant friction between the clip and sheet due to straining of the car, and the presence of moisture and grit under the clip.

My invention consists in the provision of 25 an improved means for attaching the sections of a sheet metal covering of a car roof to the car structure, whereby there is obtained great freedom of movement of the sections with respect to the substructure and 30 the rusting out of the sheets under or near the attaching means is overcome, and in the particular construction, arrangement and combination of the various parts whereby 35 this is accomplished, as more fully herein-after described and particularly pointed out in the claims.

For the purpose of more fully illustrating my invention I have appended the accompanying drawings, wherein like symbols are 40 used to designate like parts wherever they occur.

In the drawings:—Figure 1 is a partial section through the eaves of a car transverse to the longitudinal axis thereof; Fig. 2 is a 45 side elevation of my improved roof clip; Fig. 3 is a front elevation of the same, and Fig. 4 is a section through the clip on the line 4—4 of Fig. 2, showing a seam in section arranged therein.

50 In the drawings 5 is the side plate of a car, 6 the side sheathing, 7 the fascia, 8 the roof sheathing, 9 and 10 the metal roof sheets connected by the upstanding seam 22, 11 a hood clip for covering the ends of the 55 seam connecting the roof sheets and securing the sheets loosely upon the roof substructure,

12 a bolt for securing the clip to the fascia, and 13 is a nail to provide additional securing means for the clip. The clip itself comprises a base portion 14 provided with a hole 60 15 for the nail and a square hole 16 for the bolt and connected to the hood portion 17 by yokes or straps 18 which yoke portions are spaced away from the under face of the base portion so that when the clip is applied to the car a space is left between the fascia and the yoke portions, into which space the turned down ends 19 of the roof sheets extend and in which they can have a limited amount of play. The hood portion 17 has 65 at the lower edges of its side faces curved or dished flanges 20, which flanges have extensions 21 projected beyond the open side of the hood. The inner ends of these extensions 21 are spaced so far from the point of attachment of the clip to the fascia that in case the angle between the side and roof of the car becomes more obtuse through any cause and there is any tendency for the inner ends of the flanges to be jammed down on 70 the roof sheets, the result will be the bending of the clip at the yoke portions 18 rather than the clamping of the roof sheets, due to the long leverage of the extremities of the flanges with respect to the point of attachment of the clip. These flanges on account 75 of their arrangement and peculiar conformation not only present a broad under surface free from sharp edges and so unlikely to cut the roof sheets but are spaced sufficiently far apart so that in case there is any tendency for the clip, either through accident, or careless workmanship in its application to the car, to turn upon the bolt 12, which would result in binding the roof sheet 80 under one of the flanges, this tendency is largely overcome, and the likelihood of the roof sheet becoming clamped from movement on the substructure is much less than where the older type of clip is used. Moreover the wide spacing apart of the flanges 85 enables a space of at least the width of the seam to be left between the inner faces of the hood and the seam on either side thus providing adequate room for movement of 90 the roof sections longitudinally on the substructure. The spacing of the yokes 18 away from the side of the car not only enables the turned down edges of the roof sheets to have free play over the eaves, but 95 enables the front end of the hood to be closed by the front side wall 23 to prevent 100

110

the weather from blowing into the open end of the seam, while any dirt or water collecting beneath the hood portion can readily escape through the opening 24 below the 5 front wall. Moreover the front wall 23 is spaced away from the end of the seam, thus allowing the roof sheets considerable movement on the substructure transverse to the longitudinal axis of the car.

10 In applying the roof clip to the car roof, the workman, after positioning the roof sheets upon the substructure, places the clip centrally over the seam and marks the place for the bolt 12, then removes the clip and 15 bores a hole through the fascia, side sheathing and side plate for the bolt. The clip is then replaced in position and the bolt 12 is inserted and made fast. The nail 13 is then driven as an additional securing means.

20 This method of applying the clip insures that the flanges 20 shall be spaced slightly above the roof sheets, and shall not bind them tightly, but will allow the roof sheets to move on the roof substructure. The clip 25 once properly applied in this manner, there is very little danger of its becoming knocked sidewise along the eaves so as to force one of the flanges to cut into the roof sheet under it, because of the provision of the two 30 points of attachment of the clip to the substructure, and the wide spacing of the flanges. The lower surface of each flange being curved insures that even though the clip be improperly applied, or knocked out 35 of place through accident, the contacting surface between either flange and the roof sheet beneath it will have considerable area, and be free from sharp edges or corners.

My invention resides in the particular arrangement of parts as above described and 40 what I desire to claim and secure by Letters Patent is:

1. In a car roof, composed of roof sheets connected to each other by upstanding seams 45 transverse to the longitudinal axis of the car, and extending to the eaves of the car, a clip for movably holding the roof sheets on the car at the eaves, said clip comprising a base portion secured to the side of the car 50 below the eaves at two points in vertical alignment, a hood portion covering the open end of the seam and spaced from the top of the seam, and spaced from the sides and end of the seam a distance greater than the 55 width of the seam, said hood portion having a flange with a curved lower surface extending laterally from the lower edge of each side and adapted to bear on the roof sheets, said flanges having extensions beyond the 60 open side of the hood, and said flanges be-

ing connected to the base portion by yokes spaced from the side of the car and from each other, thus providing an opening for the escape of small particles from under the hood, substantially as described.

65

2. A clip for car roofs composed of roof sheets connected to each other by upstanding seams transverse to the longitudinal axis of the car, said clip comprising a base portion adapted to be secured to the side of a 70 car below the eaves, a hood portion having a front wall and side walls, the distance between the side walls within the hood portion being over twice the width of the seam connecting the roof sheets, said side walls having lateral flanges with curved lower surfaces, said flanges having extensions beyond the open side of the hood, said flanges being connected to the base portion by yokes spaced from each other and of less thickness than the base portion, to form an opening below the front wall of the hood.

75

3. A clip for car roofs composed of roof sheets connected to each other by upstanding seams transverse to the longitudinal axis 80 of the car, said clip comprising a base portion adapted to be secured to the side of a car below the eaves, a hood portion having a front wall and side walls, the distance between the side walls within the hood portion 85 being over twice the width of the seam connecting the roof sheets, said side walls having lateral flanges with curved lower surfaces, said flanges being connected to the base portion by yokes spaced from each other and from the eaves, to form an opening below the front wall of the hood and a recess for the downturned edges of the roof sheets.

90

4. A clip for car roofs composed of roof 100 sheets connected to each other by upstanding seams transverse to the longitudinal axis of the car, said clip comprising a base portion adapted to be secured to the side of a car below the eaves, a hood portion having 105 side walls, the distance between the side walls within the hood portion being over twice the width of the seam connecting the roof sheets, said side walls having lateral flanges with curved lower surfaces, said flanges having extensions beyond the open 110 side of the hood, said flanges being connected to the base portion by yokes spaced from each other and of less thickness than the base portion to form an opening at the front 115 of the hood.
